UNITED STATES PATENT OFFICE

CARROL A. LOOK, OF HUNTINGTON PARK, CALIFORNIA

DESIGN FOR A SIRUP DISPENSER

Application filed July 15, 1929. Serial No. 32,056. Term of patent 7 years.

To all whom it may concern:

Be it known that I, CARROL A. LOOK, a citizen of the United States, residing at Huntington Park, in the county of Los Angeles and State of California, have invented a new, original, and ornamental Design for Sirup Dispenser, of which the following is a specification, reference being had to the accompanying drawing, forming part thereof.

Fig. 1 is a view in front elevation of a sirup dispenser showing my new design.

Fig. 2 is a view in side elevation of the same.

I claim:

The ornamental design for a sirup dispenser, as shown.
